Primary Examiner — Samantha Q Lawrence(74) *Attorney, Agent, or Firm* — Ashley Law Firm P.C.; Stephen S. Ashley, Jr.(57) **CLAIM**

I claim the ornamental design for a blood sampling device, as shown and described.

DESCRIPTION

FIG. 1 is a perspective view of the blood sampling device according to the invention;

FIG. 2 is a left side view of the blood sampling device; FIG. 3 is an inverted right side view of the blood sampling device;

FIG. 4 is a front elevation of the blood sampling device; FIG. 5 is a top plan view of the blood sampling device; FIG. 6 is a rear elevation of the blood sampling device; and, FIG. 7 is a bottom plan view of the blood sampling device. The broken lines shown in FIGS. 1-3 illustrate portions of the blood sampling device that form no part of the claimed design.
